UNITED STATES PATENT OFFICE.

EGBERT C. COOK, OF CHICAGO, ILLINOIS.

PORTABLE HAMMOCK-SUPPORT.

SPECIFICATION forming part of Letters Patent No. 292,204, dated January 22, 1884.

Application filed June 23, 1883. (No model.)

To all whom it may concern:

Be it known that I, EGBERT C. COOK, of Chicago, in the county of Cook and State of Illinois, have invented certain new and useful 5 Improvements in Portable Hammock-Supporters, of which the following, in connection with the accompanying drawings, is a specification.

In the drawings, Figure 1 is a side elevation of a portable hammock-support embodying my 10 invention. Fig. 2 is an end view of the same. Fig. 3 is a horizontal section taken above the table, as at xx . Fig. 4 is a sectional detail showing the construction of the upper part of the frame. Fig. 5 is a detail showing the folding 15 end piece. Fig. 6 is a detail showing the mode of securing the folding legs to the base-piece. Fig. 7 is a section in the plane of the line $x'x'$, Fig. 6, and Fig. 8 is a detail showing the construction of the lower part of the frame.

20 Like letters of reference indicate like parts. My purpose is to make a portable hammock-supporter which may be compactly folded for transportation, which may be taken apart and arranged together with facility, and which 25 shall be extensible.

A A represent the end posts or standards, and B B are base-pieces, from the central parts of which the posts A A project vertically.

I deem it preferable, in order to retain the 30 posts A A firmly in place, to make tenons $a a$ on the lower ends thereof, and to mortise the base-pieces B B correspondingly to receive the said tenons; but these tenons and mortises are not absolutely essential, as will hereinafter 35 more fully appear. C C are legs or braces hinged at their upper ends to the sides of the posts A A, as shown at $b b$. The lower ends of these legs enter mortises $c c$ in the base-pieces B B, as is clearly indicated in Fig. 6.

40 D D are plates pivoted near one corner to the base-pieces B B. These plates are adapted to rest firmly on the base-pieces B B, and also to overlap the legs or braces C C, as is plainly indicated in Figs. 2, 6, and 7.

45 E E are removable headed bolts passing upward through the base-pieces B B and through the plates D D, the heads of the said bolts being downward; and F F are nuts run upon the upper or screw-threaded ends of the said bolts.

50 These bolts are so located as to lock the plates D D in such a position as to retain the lower

ends of the legs C C in the mortises $c c$ when the nuts F F are run upon the bolts.

G G' are longitudinal bars, the outer ends of which have tenons $d d$, entering the inner 55 faces of the posts or uprights A A. The other or inner ends of these bars overlap each other, and e e are holes in the parts G and G'.

H H are headed bolts, each passing through a hole in the part G, and also through a hole 60 in the part G', and I I are nuts run upon the lower or screw-threaded ends of the said bolts.

J J are horizontal bars hinged at their outer ends to the inner faces of the posts A A, near the lower ends of the latter. The inner ends 65 of these bars J J overlap each other, in like manner as do the bars G G', and are in like manner connected by means of bolts and nuts, as shown at K K, Fig. 1.

L L are inclined braces extending from the 70 posts A A downward and inward to the bars J J. The ends of these braces are provided with tenons, by preference, which enter mortises in the posts A A and bars J J.

M M are hooks connecting the lower portions of the braces L L to the bars J J, and N 75 are hooks connecting the bars G G' to the posts A A.

O is the hammock, the eyes or loops of which pass through holes $h h$ in the upper parts of 80 the posts A A, and are connected to eyes or staples $h' h'$, near the lower part of the said posts, by means of cords i i, as shown in Figs. 1 and 2.

P is the awning, and Q Q are bars or rods, 85 to which the ends of the awning are attached.

R R are headed bolts passing freely through the rods Q Q and the posts A A.

S S are nuts run upon the outer or screw-threaded ends of the bolts R R, the heads of 90 the bolts being in contact with the inner sides of the bars Q Q.

I make the base-pieces B B, the posts A A, the legs C C, the braces L L, and the bars G G' and J J of wood.

T is a strip of sail-canvas of the ordinary width, hemmed at the ends to receive rods or end bars, T' T', which I secure to the posts A A in like manner as the bars or rods Q Q are secured thereto. This strip is located at about 100 the height indicated in Fig. 1, and when applied is intended to serve as a detachable ta-

ble. To set up this frame, I set the posts A A vertically on the base-pieces B B and place the lower ends of the legs C C in the sockets e e, first unscrewing the nuts F F, removing the bolts E E, and turning the plates D D around on their pivots, so as to expose those openings or sockets. The position of the plates D D when in position to expose the sockets e e is indicated by the dotted lines at D' in Fig. 5. 5
10 I then lock the lower ends of the legs C C in position by turning the plates D D to the position shown by the full lines in Fig. 5, inserting the bolts E E and applying the nuts F F. I then lower the bars J J and arrange the braces L L in place and secure them by means of the hooks M M. The bars G G' are then arranged in place and secured by means of the hooks N N. These two halves of the frame are connected by means of the bolts H H and 20 those shown at K K, the frame or support being made either longer or shorter by arranging the said bolts either in one or the other sets of openings made to receive them. The awning may then be applied by passing the bolts R R through the bars Q Q and the posts A A, and by applying the nuts S S. The awning may be tilted as may be desired by loosening the nuts S S slightly, inclining the rods Q Q, or setting them at the desired angle, and 30 then tightening the nuts S S. The hammock may then be swung or attached to the frame by passing the loops or eyes thereof through the holes h h in the posts A A and connecting the cords i i to the staples or fastenings h h'. The table T may be arranged in place in like manner as the awning P is applied, and is cut away at the ends, as shown at j j, to receive the braces L L. 35

It will be perceived that both the hammock and the awning may be applied and removed with facility.

To take down the frame, I unfasten the

braces L L and detach them, and remove the bolts passing through the bars G G' and J J, and unlock the lower ends of the legs C C by 45 removing the nuts F F and bolts E E and turning the plates D D so that those legs may be lifted from their sockets in the base-pieces B B. The bars J J and legs C C may now be folded up compactly against the legs A A, the latter of which may also be removed or separated from the base-pieces B B. It is to be understood, of course, that the bars G G' are to be unhooked from the posts A A. 50

It will be perceived that this hammock-support may not only be easily set up and taken down, but that it may also be very compactly folded and packed for transportation.

The detachable table will be serviceable at 60 picnics and lawn-parties, being easily applied and removed, and when used the hammock may either be temporarily detached from its supports or folded up over the bars above it.

The awning and table may be rolled compactly on one of the end bars after the latter 65 are detached from the posts A A; or they may be otherwise compactly arranged.

Having thus described my invention, what I claim as new, and desire to secure by Letters Patent, is—

The combination of the posts or standards A A, the detachable feet or base-pieces B B, the folding legs or braces C C, hinged at their upper ends to the said posts, the folding and extensible bars J J, hinged to the said posts 70 and detachably connected to each other, the detachable extensibly-connected bars G G', the detachable braces L L, the hammock, and the tilting awning, substantially as and for the purposes specified. 75

EGBERT C. COOK.
